Attorney

UNITED STATES PATENT OFFICE.

CHARLES M. FINLEY, OF BERWICK, ILLINOIS.

EARTH-AUGER.

1,177,406.

Specification of Letters Patent. Patented Mar. 28, 1916.

Application filed November 27, 1915. Serial No. 63,825.

To all whom it may concern:

Be it known that I, CHARLES M. FINLEY, a citizen of the United States, residing at Berwick, in the county of Warren and State 5 of Illinois, have invented certain new and useful Improvements in Earth-Augers, of which the following is a specification, reference being had to the accompanying drawings.

10 This invention relates to certain improvements in earth augers, and it is an object of the invention to provide a device of this general character of a novel and improved construction whereby it may be employed 15 with convenience and facility and whereby a hole, preferably for a post, may be produced within a minimum of time.

The invention consists in the details of construction and in the combination and arrangement of the several parts of my improved earth auger whereby certain important advantages are attained and the device is rendered simpler, less expensive and otherwise more convenient and advantageous for use, all as will be hereinafter 25 more fully set forth.

The novel features of the invention will be carefully defined in the appended claims.

In order that my invention may be the 30 better understood, I will now proceed to describe the same with reference to the accompanying drawings, wherein—

Figure 1 is a view in elevation of an earth auger constructed in accordance with an 35 embodiment of my invention; Fig. 2 is a view in bottom plan, on an enlarged scale, of the device as disclosed in Fig. 1; Fig. 3 is a sectional view taken substantially on the line 3—3 of Fig. 1, the cylindrical body 40 comprised in the invention being shown in fragment; Fig. 4 is a fragmentary view, partly in elevation and partly in section, illustrating a certain detail of the invention as herein set forth; and Fig. 5 is a fragmentary sectional view illustrating a further detail of the invention as herein included.

As disclosed in the accompanying drawings, 1 denotes a cylindrical tubular body of predetermined dimensions and having 50 its upper end spanned by the rigid bail 2 with which the handle member 3 is operatively engaged, said handle member including the cross bar 4 in order to permit axial rotation being imparted to the device 55 with convenience and facility.

Engaged with the lower or opposite end

of the body is the cutter head 5 including a marginal flange 6 overlying the outer face of the body 1 and suitably secured thereto, as indicated at 7. I wish to be understood 60 that I do not desire to limit myself as to the particular mounting of the cutter head 5 upon the body 1.

The head 5 overlies the lower end of the body 1 and has a central opening 8 having 65 in communication therewith the oppositely directed slots 9 arranged in radial alignment, said slots terminating at the engaging flange 6. Portions of the body 10 of the cutter head at opposite sides of the slot 70 9 are flat for a predetermined distance, as at 11, and are then gradually depressed, as at 12, both circumferentially and radially to afford entrance openings 14 for the earth as loosened, it being understood that said 75 loose earth upon axial rotation of the body 1 enters within the body 1 so that the same may be readily elevated. It is to be noted that the sectors afforded by the depressed portion 12, are in excess of 90°. The vertical walls 15 afforded by the depressed portions 12 are bowed or curved outwardly in cross section in order to facilitate the cutting operation and I find it of particular advantage to provide the free margins of 80 the depressed portions 12 with the cutter blades 16 and the free edges of the vertical walls 15 with the cutter blades 17 which preferably are removable in order that the same may be replaced as the requirements 85 of practice may necessitate.

From the foregoing description, it is thought to be obvious that an earth auger constructed in accordance with my invention is of an extremely simple and comparatively inexpensive nature and is particularly well adapted for use by reason of the convenience and facility with which it may be assembled, and it will also be obvious that my invention is susceptible of some change 95 100 and modification without material departure from the principles and spirit thereof and for this reason I do not wish to be understood as limiting myself to the precise arrangement and formation of the several parts herein shown in carrying out my invention in practice.

I claim:

1. An earth auger comprising a cylindrical tubular member provided with operating means, and a cutter head overlying the lower end of said body, said cutter head 110

having substantially radially alined slots, said head being also provided with diametrically opposed sectors gradually depressed radially from the center and circumferentially toward the slots, an edge of each of the slots constituting a radius for the adjacent sector.

2. An earth auger comprising a cylindrical tubular member provided with operating means, and a cutter head overlying the lower end of said body, said cutter head having substantially radially alined slots, said head being also provided with diametrically opposed sectors gradually depressed radially from the center and circumferentially toward the slots, an edge of each of the slots constituting a radius for the adjacent sector, said head being provided with an opening at its axial center with which the slots communicate.

Copies of this patent may be obtained for five cents each, by addressing the "Commissioner of Patents, Washington, D. C."

3. An earth auger comprising a cylindrical tubular member provided with operating means, and a cutter head overlying the lower end of said body, said cutter head having substantially radially alined slots, 25 said head being also provided with diametrically opposed sectors gradually depressed radially from the center and circumferentially toward the slots, an edge of each of the slots constituting a radius for the adjacent 30 sector, the vertical walls afforded by the depressed sectors of the head being bowed outwardly in cross section.

In testimony whereof I hereunto affix my signature in the presence of two witnesses. 35

CHARLES M. FINLEY.

Witnesses:

BURR B. FINLEY,
HARRY W. CARR.
